United States Patent Office.

HERMANN ILENBURG, OF PHILADELPHIA, PENNSYLVANIA, ASSIGNOR TO MACKELLAR, SMITHS & JORDAN, OF SAME PLACE.

Design No. 4,061, dated May 24, 1870.

DESIGN FOR TYPE.

The Schedule referred to in these Letters Patent and making part of the same

---

To all whom it may concern:

Be it known that I, HERMANN ILENBURG, assignor to MACKELLAR, SMITHS, & JORDAN, of the city and county of Philadelphia, Pennsylvania, have originated and produced a new and original Design for a Printing-Type, of which the following is a specification.

The nature of my design is fully represented in the accompanying impressions, in which the capital and lower-case letters of the alphabet are exhibited.

I claim as my invention—

The design for printing-type, as shown.

H. ILENBURG.

Witnesses:

C. G. HUCH,

GEO. WM. WITHAM.
